(57) **CLAIM**

The ornamental design for a breathing mask, as shown and described.

DESCRIPTION

FIG. 1 is a perspective view of the breathing mask; FIG. 2 is a left side view of the breathing mask; FIG. 3 is a bottom view of the breathing mask; FIG. 4 is a right side view of the breathing mask; and, FIG. 5 is a back view of the breathing mask. The broken lines illustrate environmental structure of the breathing mask, which forms no part of the claimed design.
